(57) **CLAIM**

An ornamental design for a lug wrench extender, as shown and described.

DESCRIPTION

FIG. 1 is a perspective view of the lug wrench extender; FIG. 2 is a second perspective view of the lug wrench extender thereof;

FIG. 3 is an enlarged perspective view of the curved gripping member of the lug wrench extender thereof; and,

FIG. 4 is a second enlarged perspective view of the curved gripping member of the lug wrench extender of FIG. 1.

The broken lines in FIGS. 2 and 3 are included for the purpose of illustrating the lug wrench extender attached to a lug wrench in FIG. 2 and FIG. 3 shows a surface treatment on the gripping member, none of which forms a part of the claimed design.

1 Claim, 4 Drawing Sheets
